UNITED STATES PATENT OFFICE.

ATHERTON SEWALL, OF BOSTON, MASSACHUSETTS.

DESIGN FOR A GOLF-TEE.

SPECIFICATION forming part of Design No. 31,878, dated November 21, 1899.

Application filed August 26, 1899. Serial No. 728,626. Term of patent 14 years.

To all whom it may concern:

Be it known that I, ATHERTON SEWALL, a citizen of the United States, residing at Boston, in the county of Suffolk and Commonwealth of Massachusetts, have invented and produced a new and original Design for a Golf-Tee, of which the following is a specification.

Figure 1 is a perspective view of a golf-tee, illustrating my design; and Fig. 2 is a side elevation thereof.

The leading feature of my design for a golf-tee consists in an imperforate base having a flat bottom and a central upturned solid column much smaller than the base rising from the top thereof and having a depression in its upper end, the top of the base rising gradually from its periphery toward and merging into the foot of the column by a curved surface.

The golf-tee in accordance with my design

has an imperforate base a , flat on its bottom and shown as circular, and an upturned solid column a' of much smaller diameter than the base rising from the top thereof at its center and joined thereto by a graceful curved surface, the upper end of the column having a cup-like depression a^2 therein, the top of the base rising gradually from its periphery to the curved surface and merging therewith.

Having fully described my design, what I claim, and desire to secure by Letters Patent, is—

The design for a golf-tee, substantially as herein shown and described.

In testimony whereof I have signed my name to this specification in the presence of two subscribing witnesses.

ATHERTON SEWALL.
